UNITED STATES PATENT OFFICE

PHILIP C. WENTWORTH, OF PROVIDENCE, RHODE ISLAND, AND JAMES H. AVERY, OF FRANKLIN, MASSACHUSETTS, ASSIGNEES TO NATIONAL RING TRAVELER CO., OF PROVIDENCE, RHODE ISLAND, A CORPORATION OF RHODE ISLAND

STROBOSCOPE

Application filed June 10, 1931. Serial No. 543,314.

This invention relates to stroboscopes and is particularly adapted for use with such equipment as ring spinning and twisting equipment where the problem is to observe and intelligently analyze the many varying factors involved in order to establish the proper relationship between the spindle, ring and traveler used in ring spinning and twisting yarn. These varying factors all have a definite bearing upon the ultimate result obtained and all have a definite relationship to each other and to the particular type of observation apparatus employed. The existence of these factors has always been known, but on account of the lack of any reliable apparatus for positively observing their effects under conditions of actual service, such effects could only be guessed at and any change or correction offered as a remedy was apt to be more theoretical than actually justified by positive observation.

For example, spindle speeds often vary, even where the spindles are driven from a common driving source, and the traveler lags with reference to the spindle speed. Such traveler lag has a definite bearing upon the proper functioning of the traveler, as does the weight of the traveler, the angle of the thread relative to the axis of the spindle, the difference in tension during the rising and falling phases of the rail, and the constantly increasing diameter of the thread being laid on the bobbin. These, and many other factors, all contribute towards variations in the quality of the yarn being spun or twisted, and hence must all be taken into consideration in determining such fundamental matters as traveler weight, spindle speed, etc.

The general object of our invention therefore is to provide a convenient and simple apparatus for stroboscopically determining the speeds of the spindle and traveler and for observing the relation of the traveler to the ring at the speed obtained. By means of these observations we are enabled to establish the necessary factors for determining whether or not the ring and the traveler are in proper relationship to each other. As previously suggested, such relationship may be a matter of traveler speed or

spindle speed, or may be a combination of either of these. Having established by such observation the particular factors involved for any given installation, the proper corrective steps next to be taken may then be accurately determined. When such corrective steps are made, the mill-owner may then obtain that efficiency of operation which has been so long desired in the ring spinning and twisting art and which would be represented by the theoretically attained condition of a traveler freely "floating" on the ring.

As illustrative of the principles of our invention we show in the accompanying drawing a form of stroboscope operating upon the principle of periodic interruption of illumination. Such apparatus is illustrative rather than limiting, as the stroboscopic principle may be attained in various other manners.

In such drawing:—

Fig. 1 is a plan view of a stroboscope in accordance with our present invention, and

Fig. 2 is a side elevation thereof.

Since one of the desiderata in a device of this character is that the apparatus shall be capable of ready transportation to the spinning frame or other object to be observed, we have illustrated a portable stroboscope of light and compact form in this drawing. As such, our stroboscope comprises a base 1 on which is mounted a variable speed motor 2 which may be belted as at 3 through change speed pulleys 4 and 5 and 6 and 7 to a driven shaft 8.

The driven shaft is formed as a pair of aligned sections flexibly connected as at 9. The two shaft sections are mounted in suitable bearings 10, 11 and 12. One shaft section, here indicated as the shaft section 13, is an interrupter shaft controlling an interrupter 14. The interrupter 14 is a make and break device of any ordinary type adapted intermittently to make and break the circuit through a cable 15 which supplies current to a projector 16 by means of which a beam of light may be periodically flashed onto any rotating part which is to be observed.

Where the observation apparatus is mechanical rather than electrical we may use

the interference type of vision interrupter in place of the intermittently flashing projector, such interrupter being an apertured disc or the like for periodically interrupting vision of the part to be observed, the number of interruptions corresponding to the speed of the interrupter shaft.

The opposite section 8 of the sectional driven shaft has attached to its outer end a 10 tachometer or other device 17, to indicate the speed of the sectional driven shaft as driven by the motor.

We have also provided a conventional belt 15 tightener 18 for taking up any slack in the driving belt between the motor shaft and the shaft 8, as well as a mechanical brake or other friction retarder 19 for manually slowing down the speed of the driven shaft when desired.

20 In accordance with our present concept, we provide means whereby the speed of the motor may be positively controlled by regulating the input of operating current. Such a device is indicated at 20 and consists of a 25 variable resistance through which the current to the motor is passed. The resistance apparatus 20 is provided with a manually operable control knob 21 by means of which the input of the current to the motor may 30 be manually regulated and with a push button 22 functioning as an accelerator by means of which the motor may be quickly speeded up independently of the control knob 21 in the event that the operator does not 35 wish to take the time to attain the desired speed by the slower method of increasing the input of the current by means of the control knob.

40 In operation, the apparatus is positioned adjacent the spinning or twisting frame which is to be observed and the motor 2 and flash projector 16 are connected up with the current source, preferably by means of independent switch controls.

45 The variable resistance 20 enables the input of current to the motor to be positively regulated and thus the speed of the motor brought up to the desired speed, which speed will approximate the speed of the spindle to 50 be observed. By manipulating the control knob 21 of such resistance 20, the motor may readily be maintained at the desired speed, the accelerator button 22 permitting the motor to be speeded up as needed.

55 The rotation of the motor shaft is transmitted through belt 2 and chain speed pulleys 4 or 5 and 6 or 7 to the driven shaft 8 with no appreciable loss of speed, and the 60 speed of the driven shaft 8 and thus the flash frequency of the flash projector is visually indicated to the observer by means of the tachometer 17 which is driven from shaft 8. Should for any reason it be desired to 65 slow down the flash frequency of the pro-

jector, this may be done by means of the friction brake 19 on the driven shaft 8.

Under usual operating conditions, the traveler will appear to be standing substantially still on the ring or if not standing absolutely still, to momentarily move slightly in one direction or the other, as its lag behind the speed spindle is never absolutely constant. The estimated lag of the traveler is usually about 10% of the required traveler speed. 70 The tachometer furnishes a convenient means for determining the relative speed of the traveler and its percentage of lag may be approximately fixed by varying the speed of the motor through the extremely sensitive control afforded by the variable resistance 75 20. The traveler may be brought momentarily to a position at which it appears to be substantially stationary and may be held in such position sufficiently long to enable its 80 position on the ring to be definitely observed. This is important in determining whether or not a traveler is too light or too heavy for the particular grade of yarn being spun or twisted. If the traveler is too light for 85 the yarn being used or for the particular speed at which the spindle is being rotated, the traveler will appear to be thrown outwardly by centrifugal action. If too heavy, the traveler will tend to lag so much that it 90 will appear to be drawn radially of the ring. In either case the result is to produce an undesirable friction on the ring at the horns 95 of the traveler. Such friction is responsible for the lag of the traveler. More than this, it produces destructive wear on the traveler 100 horns and the expensive traveler ring and causes the yarn being spun or twisted to vary in diameter.

105 By our invention therefore we are able to analyze the action of any spindle equipment which is not functioning properly or which appears to be functioning properly but actually is not, and as a result of our 110 study to determine which of the several factors of spindle speed, traveler speed, traveler lag, traveler weight, angle of thread relative to the axis of the spindle, difference in tension between the rising and falling movements of rail, constantly increasing diameter 115 of the thread being laid on the bobbin, may be involved and intelligently to prescribe the required corrective steps to be taken.

120 Various modifications in the construction and operation of our device may obviously be resorted to if within the spirit and scope of our invention without departing from the limits of the appended claims.

125 What we therefore claim and desire to secure by Letters Patent is:

1. Stroboscopic apparatus for determining the necessary factors to establish the proper relationship between the spindle, ring and traveler used in ring spinning and twisting yarn, comprising a variable speed motor, an 130

interrupter shaft driven from said motor at speeds regulatable to the varying speed of the spindle and traveler relative to each other, a variable resistance for controlling the input of current to said motor, an interrupter driven from said driven shaft a flash light manipulatable with reference to the part or parts to be observed and adapted to be periodically flashed by said interrupter in synchronism therewith for determining stroboscopically the speed of the spindle and traveler relative to each other so that the relation of the traveler to the ring may be observed with the stroboscope at the speed obtained, and a tachometer driven from said driven shaft for visually indicating the speed of said driven shaft.

2. Stroboscopic apparatus for determining the necessary factors to establish the proper relationship between the spindle, ring and traveler used in ring spinning and twisting yarn, comprising a variable speed motor, an interrupter shaft driven from said motor at speeds regulatable to the varying speed of the spindle and traveler relative to each other, a variable resistance for controlling the input of current to said motor, said resistance including a control knob by means of which the resistance to said motor may be manually regulated and an accelerator by means of which the motor may be instantly speeded up, an interrupter driven from said driven shaft a flash light manipulatable with reference to the part or parts to be observed and adapted to be periodically flashed by said interrupter in synchronism therewith for determining stroboscopically the speed of the spindle and traveler relative to each other so that the relation of the traveler to the ring may be observed with the stroboscope at the speed obtained, a tachometer driven from said driven shaft for visually indicating the speed of said driven shaft and a frictional retarding device for said driven shaft manually operable to reduce the speed of said shaft.

3. Stroboscopic apparatus for determining the necessary factors to establish the proper relationship between the spindle, ring and traveler used in ring spinning and twisting yarn, comprising a variable speed motor, an interrupter shaft driven from said motor at speeds regulatable to the varying speed of the spindle and traveler relative to each other, a variable resistance for controlling the input of current to said motor, an interrupter driven from said driven shaft a flash light manipulatable with reference to the part or parts to be observed and adapted to be periodically flashed by said interrupter in synchronism therewith for determining stroboscopically the speed of the spindle and traveler relative to each other so that the relation of the traveler to the ring may be observed with the stroboscope at the speed obtained.

4. Stroboscopic apparatus for determining the necessary factors to establish the proper relationship between the spindle, ring and

traveler used in ring spinning and twisting yarn, comprising a variable speed motor, an interrupter shaft driven from said motor at speeds regulatable to the varying speed of the spindle and traveler relative to each other, a variable resistance for controlling the input of current to said motor, said resistance including a control knob by means of which the resistance to said motor may be manually regulated and an accelerator by means of which the motor may be instantly speeded up, an interrupter driven from said driven shaft a flash light manipulatable with reference to the part or parts to be observed and adapted to be periodically flashed by said interrupter in synchronism therewith for determining stroboscopically the speed of the spindle and traveler relative to each other so that the relation of the traveler to the ring may be observed with the stroboscope at the speed obtained, a tachometer driven from said driven shaft for visually indicating the speed of said driven shaft and a frictional retarding device for said driven shaft manually operable to reduce the speed of said shaft.

In testimony whereof we affix our signatures.

PHILIP C. WENTWORTH.
